HOSE SUPPORTER

Adolph J. Sobel, Roslyn, N.Y., assignor to The Governor Fastener Company, Meriden, Conn., a corporation of Connecticut

Filed Feb. 25, 1960, Ser. No. 59,528

Term of patent 14 years

(Cl. D17—3)

FIG. 1

FIG. 2

FIG. 4

Fig. 1 is a top plan view of a hose supporter embodying my new design;

Fig. 2 is a front elevational view thereof;

Fig. 3 is an edge elevational view as seen from the right of Fig. 2; and

Fig. 4 is a bottom plan view thereof.

I claim:

The ornamental design for a hose supporter, as shown.
